UNITED STATES PATENT OFFICE.

HERMANN FALKENBACH, OF NEW YORK, N. Y.

COACHMAN'S HAT.

SPECIFICATION forming part of Letters Patent No. 622,040, dated March 28, 1899.

Application filed January 27, 1898. Serial No. 668,125. (No model.)

To all whom it may concern:

Be it known that I, HERMANN FALKENBACH, a citizen of the United States, residing in the city, county, and State of New York, 5 have invented certain new and useful Improvements in Coachmen's Hats, of which the following is a specification.

Waterproof hats—such as are used by coachmen of livery-stables, families, &c.—were heretofore made of cassimere which was stiffened with shellac. These hats were objectionable for several reasons, first, because they do not sufficiently resist the influence of moisture, soon getting out of shape and un- 15 sightly, and, secondly, because under the combined influence of light and moisture they lose their color and become shabby and rusty, so that after having been worn a certain time they present a very disagreeable appearance.

20 The object of my invention is to supply the coachmen and drivers of public and private conveyances in general with an improved waterproof hat that is not liable to get out of shape, nor liable to change its color, and that 25 will outlast several hats as heretofore made.

The invention consists of certain features of construction to be hereinafter described and then claimed.

In the accompanying drawings, Figure 1 is 30 a side elevation of my improved hat. Fig. 2 is a vertical section of the same on a larger scale; and Fig. 3 is a front view of a piece of broadcloth provided with a vulcanized layer of rubber at its under side as used by me in 35 the manufacture of waterproof hats.

Referring to the drawings, A represents the body of my improved coachman's hat. This body is made in the usual manner of several layers of linen B, connected by intermediate 40 layers of shellac until the required thickness and strength are obtained. The brim of the hat is made of a greater number of layers than the body and crown of the hat. The entire body of the hat is then covered by a 45 layer C of broadcloth, which is first cut into proper shape, the parts being stitched together and then applied to the hat and cemented on by heating-irons. The body of

the hat is lined with the usual silk or satin lining D, which is pasted to the linen body B 50 in the usual manner. The broadcloth used for the covering-layer is made waterproof by laying a thin layer C' of rubber on the under side and vulcanizing the same in the well-known manner. This has the advantage of 55 imparting to the hat a perfectly waterproof layer, so that the water cannot penetrate into the shellac-covered linen body and so that the body cannot change its shape even when exposed to a drenching rain; nor will the 60 broadcloth change its color under the influence of sun and rain, so that thereby a very durable and elegant hat for coachmen's use is obtained. The same construction is also applicable to policemen's, army, and other 65 hats in which it is desired to retain the shape and color of the hat and prevent deformation.

It will be observed from Fig. 2 that the layer of broadcloth, which is provided with a layer of vulcanized rubber at its under side, is applied both to the upper and lower sides of the hat-brim.

Having thus described my invention, what I claim is—

1. A waterproof hat, composed of a stiffened 75 and shellac-covered body, and a covering layer of broadcloth having a vulcanized layer of rubber at its under side and cemented to said body by the vulcanized rubber and the shellac of the adjacent surfaces, substantially 80 as set forth.

2. A waterproof hat, composed of a stiffened shellac-covered body provided with a brim, and a covering layer of broadcloth upon the exterior of the body and both sides of the 85 brim, said layer of broadcloth having a vulcanized layer of rubber at its under side cemented to the body and brim, substantially 90 as set forth.

In testimony that I claim the foregoing as 90 my invention I have signed my name in presence of two subscribing witnesses.

HERMANN FALKENBACH.
